UNITED STATES PATENT OFFICE.

FRANK E. MILLER AND ROBERT M. LACEY, OF NEW YORK, N. Y., ASSIGNEES TO FRANK E. MILLER RADIO CORPORATION, OF NEW YORK, N. Y.

PUSH-PULL REPRODUCER.

Application filed March 24, 1925; Serial No. 17,869. Renewed June 29, 1927.

Our invention relates to the reproduction of sound, especially adapted for use as a loud speaker in radio reception.

It is an object of our invention to make use of the push pull principle so that the energy of the reproducing magnet may be exerted in two directions simultaneously.

Our invention will be better understood by reference to illustrative embodiments thereof, to which the accompanying claims are directed as examples merely, which are described in the following specification and which are shown in the accompanying drawings forming a part thereof.

15 In the drawings Figure 1 is an end elevation partly in section; Fig. 2 is a schematic diagram of the electrical and mechanical connections; Fig. 3 is a side elevation of one portion of the diaphragm proper; Fig. 20 4 shows a plane view of a possible design in square section, and Fig. 5 is an end elevation of the design shown in Fig. 4.

Referring to Fig. 1, "L" is the connection wires from the electrical circuit, "A" is the 25 base and "B" is the outer frame of our device, "C" and "D" are the respective diaphragms proper which we prefer to connect to each stylus "H" and "G" respectively at the eccentric points "J" and "I", although these 30 may be connected at the apex of the cone-shaped diaphragm "C" and "D". "E" are the magnetic core and coils and "F" is a point of fulcrum in the stylus arms. "K" is a handle integral with the frame "B".

35 By reference to Fig. 2 it will be seen that coils "R" and "Q" connected with the electrical circuits "O" and "P" are so connected that they will function with the permanent magnets so as to give a push pull 40 action on the arm "F" revolving about the axis "M" so that if the arm "F" acts in one direction the stylus connections "H" and "G" will tend to operate in opposite directions and proportionately cause the diaphragms "C" and "D" to vibrate. If an 45 electrical current is passed through the coils causing magnetic lines of force to augment the permanent magnetization of the cores our connections are such that the poles of

the respective magnets are oppositely magnetized in polarity so that double action on the arm "F" is obtained, resulting in a push pull effect of the diaphragms "C" and "D".

In Fig. 4 we show a square section adaptation of our device. Magnets similar to the magnet "X" are mounted on the frame "U" at "V", "W" and "T", the connecting link "Y" being securely fastened to the separate sides of the frame by studs or rivets "Z Z", and provision being made to connect the arm "F" at "M" as in the circular section.

Having thus described our invention, what we claim and desire to secure by U. S. Letters Patent is:

1. A push pull reproducer comprising a 65 base, a frame mounted in said base, cusp shaped diaphragms mounted at their periphery in said frame, having stylus connections leverally operative through an electromagnet adapted to simultaneously 70 and in opposite directions operate said styli and diaphragms.

2. A push pull reproducer comprising a base, a frame mounted in said base, eccentric cusp shaped diaphragms mounted at 75 their periphery in said frame, having stylus connections leverally operative through an electromagnet adapted to simultaneously and in opposite directions operate said styli and diaphragms.

3. A push pull reproducer comprising a base, a frame mounted in said base, cusp shaped diaphragms mounted at their periphery in said frame, having stylus connections leverally operative through an electromagnet having square section cores and adapted to simultaneously and in opposite directions operate said styli and diaphragms.

4. A push pull reproducer comprising a 90 base, a frame mounted in said base, eccentric cusp shaped diaphragms mounted at their periphery in said frame, having stylus connections leverally operative through an electromagnet having square section cores 95 and adapted to simultaneously and in opposite directions operate said styli and diaphragms.

2

5. The combination in a push pull reproducer of an electromagnet having two sections and a magnetically operative arm pivotally placed between said sections free to swing in the magnetic field created thereby and leverally connected at each end with stylus arms adapted to simultaneously actuate two cusp shaped diaphragms whose pe-

ripheries are joined in the frame of said reproducer.

In witness whereof we have hereunto signed our names the 3rd day of March, 1925.

FRANK E. MILLER.
ROBERT M. LACEY.
